US00D746462S

(12) **United States Design Patent**
Mujwid(10) **Patent No.:** **US D746,462 S**
(45) **Date of Patent:** **** Dec. 29, 2015**(54) **SURGICAL INDICATORS**(71) Applicant: **AMS Research Corporation**,
Minnetonka, MN (US)(72) Inventor: **James R. Mujwid**, Edina, MN (US)(73) Assignee: **AMS Research Corporation**, Eden
Prairie, MN (US)(***) Term: **14 Years**(21) Appl. No.: **29/511,190**(22) Filed: **Dec. 8, 2014****Related U.S. Application Data**(62) Division of application No. 29/401,196, filed on Sep.
8, 2011, now Pat. No. Des. 721,807.(51) **LOC (10) Cl.** ..... **24-02**(52) **U.S. Cl.**USPC ..... **D24/155**(58) **Field of Classification Search**USPC D24/155, 133, 135, 141, 144-146
CPC .. A61F 2/0045; A61F 2/0063; A61B 17/0401

Primary Examiner — Susan Bennett Hattan*Assistant Examiner* — Charles Hanson(74) *Attorney, Agent, or Firm* — Kagan Binder, PLLC(57) **CLAIM**The ornamental design for surgical indicators, as shown and
described.**DESCRIPTION**FIG. 1 is a perspective view of a surgical indicator of my new
design;

FIG. 2 is a top view thereof;

FIG. 3 is a bottom view thereof;

FIG. 4 is a front view thereof, the back view being identical;
and,FIG. 5 is a left side view thereof, the right side view being
identical.The broken line portions of the drawings are for illustrative
purposes only and form no part of the claimed designs.**1 Claim, 3 Drawing Sheets**| (56) References Cited
